AUTOMATIC CARD-DIALING TELEPHONE DESK SET

Robert H. Hose, Mountainside, N.J., assignor to Bell Telephone Laboratories, Incorporated, New York, N.Y., a corporation of New York

Filed Dec. 8, 1960, Ser. No. 63,163

Term of patent 14 years

(Cl. D26—14)

FIG. 1

FIG. 2

FIG. 3

FIG. 4

FIG. 1 is a perspective view of an automatic card-dialing telephone desk set, showing my new design;

FIG. 2 is a side view of the automatic card-dialing telephone desk set showing my new design;

FIG. 3 is a top view of the automatic card-dialing telephone desk set, showing my new design; and

FIG. 4 is an enlarged partial cross-sectional view of the face plate of the automatic card-dialing telephone desk set taken on line 4—4 in FIG. 3.

The broken line showing of legible matter and of a telephone handset in FIG. 3 is for illustrative purposes only.

The dominant features of the design reside in the por-

tions shown in full lines, and consist primarily in the card receiving slot and the start and release control buttons above the dial position in association with the card storage wells in the rear deck.

I claim:

The ornamental design for an automatic card-dialing telephone desk set, substantially as shown and described.
